UNITED STATES PATENT OFFICE.

HATTIE J. GRINDAL, OF BANGOR, MAINE.

MATTRESS HOLDER.

Application filed July 7, 1924. Serial No. 724,665.

To all whom it may concern:

Be it known that I, HATTIE J. GRINDAL, a citizen of the United States, residing at Bangor, in the county of Penobscot and 5 State of Maine, have invented certain new and useful Improvements in Mattress Holders; and I do declare the following to be a full, clear, and exact description of the invention, such as will enable others skilled 10 in the art to which it appertains to make and use the same.

A great many metal beds are provided with vertically spaced horizontal bars at the head and foot, and the mattress often slides 15 on the spring and moves outwardly between these bars, necessitating that it be repeatedly pulled back in place, which is often very arduous. It is the object of my invention to provide a simple and inexpensive attachment 20 for beds of the character set forth, which will abut an end of the mattress (either head or foot or both) and will hold it against longitudinal sliding.

With the foregoing in view, the invention 25 resides in the novel subject matter herein-after described and claimed, the description being supplemented by the accompanying drawing.

Figure 1 is a perspective view showing the 30 invention attached to a bed.

Figure 2 is a perspective view of the attachment separate from the bed.

In the drawing above briefly described, the numeral 1 designates either the head or 35 the foot section of a bed, said section having vertically spaced horizontal bars 2 and 3 adjacent the end of the mattress 4. Very often, the mattress slides on the spring, designated in the drawing at 5, and moves 40 outwardly between the bars 2 and 3, but such an occurrence is prevented by the use of my invention, the preferred form of which is shown.

The numerals 6 designate a plurality of vertical metal bars which are adapted to 45 extend across the horizontal bars 2 and 3, the upper ends of said bars 6 having hooks 7 preferably formed by bending the bars, these hooks being adapted to engage the bar 2 as shown fully in Fig. 1. A horizontal 50 bar 8 of wood or metal extends across the bars 6 and is secured thereto by suitable fasteners 9, and in the present disclosure of the invention, it is the bar 8 which contacts with the end of the mattress to prevent it 55 from sliding outwardly between the bars 2 and 3.

The invention is simple and inexpensive and may be applied to a bed at either its 60 head or foot or at both points, as occasion 65 may require, and when in use, the mattress will be positively held against slipping end-wise from the spring, so that it is not necessary to repeatedly pull the mattress and the bed clothes back into their proper positions. 70

As excellent results may be obtained with the details disclosed, these details are preferably followed, but within the scope of the invention as claimed, numerous modifications may be made.

I claim:

A. mattress guard comprising a rigid frame composed of a plurality of flat horizontally spaced vertical bars arranged in a plane and having their upper ends bent rearwardly and downwardly to form hooks to take over one of the horizontal bars at the end of a bed, a single flat horizontal bar extending across all of said vertical bars below said hooks and being disposed flat 75 against said vertical bars, and securing elements rigidly securing said vertical bars to said horizontal bar.

In testimony whereof I have hereunto affixed my signature.

HATTIE J. GRINDAL.
